UNITED STATES PATENT OFFICE

149,746

DESIGN FOR A BROOCH PIN OR SIMILAR ARTICLE

Sylvia Hobe, New York, N. Y.

Application February 28, 1947, Serial No. 137,241

Term of patent 3½ years

(Cl. D45—19)

To all whom it may concern:

Be it known that I, Sylvia Hobe, a citizen of the United States of America, residing in New York city, county of New York, and State of New York, have invented a new, original, and ornamental Design for a Brooch Pin or Similar Article, of which the following is a specification, reference being had to the accompanying drawing, forming part thereof, wherein,

I claim:

The ornamental design for a brooch pin or similar article, substantially as shown.

SYLVIA HOBE.
